UNITED STATES PATENT OFFICE.

RALPH H. MOORE AND JOSEPH T. BUZZO, OF OAKLAND, CALIFORNIA.

AUTOMATIC SLUICING DEVICE FOR FILTERS.

1,325,449.

Specification of Letters Patent.

Patented Dec. 16, 1919.

Application filed February 8, 1919. Serial No. 275,882.

To all whom it may concern:

Be it known that we, RALPH H. MOORE and JOSEPH T. BUZZO, citizens of the United States, residing at Oakland, in the county 5 of Alameda and State of California, have invented certain new and useful Improvements in Automatic Sluicing Devices for Filters, of which the following is a specification:

10 In removing the cake from filter clothes in what are commonly termed filter presses, and particularly that type of press termed Sweetland filter, a wash water pipe extends into the filter casing and is longitudinally 15 movable and also adapted for oscillation in order that the wash water stream discharging therefrom will strike the faces of the filter clothes for their full area and wash or loosen the collected cake adhering 20 to the exterior surface thereof.

Different mechanisms have been constructed to accomplish this reciprocating and oscillating movement of the wash water pipe and the present invention relates to 25 such mechanism as has for its principal objects to provide a simple construction which is automatic in its operation, whereby the wash water pipe on arriving at the end of its stroke in either direction is automatically reversed in its movement thereby 30 overcoming the necessity of an attendant, required when manual mechanisms for this purpose are employed.

The present construction is particularly 35 designed for installation in connection with certain elements of the manual operating mechanism now supplied with filter presses of the above type, whereby the reciprocating movement is automatically reversed on 40 the pipe arriving at the end of its stroke in either direction.

With the above mentioned and other objects in view, the invention consists in the novel construction and combination of parts 45 hereininafter described, illustrated in the accompanying drawings and pointed out in the claims hereto appended; it being understood that various changes in the form, proportion, size and minor details of construction within the scope of the claims 50 may be resorted to without departing from the spirit or sacrificing any of the advantages of the invention.

To more fully comprehend the invention,

reference is directed to the accompanying 55 drawings, wherein—

Figure 1 is a view in side elevation of the preferred embodiment of our invention.

Fig. 2 is a longitudinal sectional view 60 thereof.

Fig. 3 is a transverse sectional view taken on line 3—3 of Fig. 1, viewed in the direction of the arrows.

Fig. 4 is a sectional view on line 4—4 of 65 Fig. 1.

In the drawings, the numeral 1 indicates the casing of the filter press formed with an opening 2 through which extends the horizontally disposed wash water pipe 5, the same passing through a stuffing box 3 70 which prevents leakage between the pipe and casing. The pipe is adapted for both reciprocating movement and oscillating movement within said opening 2, and at a point removed from said gland 3 is secured 75 thereto a clamp 4 from which extends a lateral arm 6, the same being connected at its free end preferably through a link mechanism with a member 7 for imparting an oscillating movement through the arm 80 6 to the pipe 5.

Rigidly secured to the pipe and surrounding the same is a threaded sleeve 8, which has threaded connection with a threaded operating nut 9, said nut being 85 split longitudinally as at 10 and said two half sections being loosely secured together by bolts 11 passing through ears 12 on said half sections. Compression springs 13 force the half sections tightly about the sleeve 8, 90 whereby the threads of the nut 9 engage the threads of the sleeve 8 with considerable friction. The nut is retained from longitudinal movement with the pipe 5 and sleeve 8 by a suitable curved plate 14, semi-circular in front elevation and receivable in an annular groove or guide 15 in the outer surface of the nut 9, said plate being supported and retained in spaced relation from the casing 1 by suitable bolts or other 100 means 16 extending laterally from the casing 1 at opposite sides of the shaft 5. This construction enables the non-rotation of the nut 9 to cause a reciprocating movement of the pipe 5 when said pipe is oscillated 105 due to the operation of the arm 6.

Extending upwardly from the plate 14 is a supporting arm 17 formed in its upper

surface with a bearing 18 which is in alignment with a corresponding bearing 18' formed in the upper end of an arm or supporting bracket 19 extending upwardly 5 from the casing 1, and rotatably mounted in said bearings are the opposite end tubular spindles 20 of an elongated cylindrical casing or pawl trip member 21, which is formed on its inner face with the oppositely disposed longitudinally extending guide grooves 22, and said casing is provided on its outer surface, adjacent one end, with the oppositely disposed cam surfaces 23 and 24, the low ends of which are arranged adjacent each other and said cams are disposed 15 in different planes transversely on the member 21. The member 21 is also provided at a point opposite the cam surfaces 23 and 24 with an outwardly projecting counterbalance weight or portion 25, and at one end of said member 21 the same is provided with lugs 26 and 27 which co-operate respectively with stationary projection 28 on the supporting arm 19 and 20 which co-operating engagement limits the rotating movement of the member 21, hereinafter described.

Rotatably mounted at its opposite ends in the tubular spindle 20 of the member 21 30 is a shaft 29 extending centrally of the member 21, and the portion thereof within the member 21 is threaded as at 30. One end of said shaft 29 extends beyond its co-operating spindle 20 and has keyed thereto 35 a driven pinion 31 which intermeshes with a driving gear 32 secured by bolts 33 to the nut 9. The connection between said bolts 33 and the ears 34 on said nut, through which the same pass, permits of a slight 40 movement of the nut forming half sections radially of the gear 32 to enable the springs 13 to yieldably maintain the nut forming half sections in tight frictional engagement with the sleeve 8. The gear 32 is preferably 45 in ring annular formation and is disposed circumferentially of the nut, adjacent one end. The nut 9 at the end opposite said gear 32 is provided with the ratchets 35 disposed circumferentially thereof, and with 50 which are adapted to contact the lower ends of pawls 36 and 37 pivotally mounted on the support 38 extending laterally from the arm 17, said pawls lying one at each longitudinal side of the nut 9, and with their upper 55 crossed ends co-operating respectively with the cam surfaces 23 and 24.

The mechanism for causing a partial rotation of the pawl trip mechanism 21 to disengage one of the pawls 36 from the ratchets 60 35 and to position the other pawl to co-operate with said ratchets on the reciprocating movement of the pipe 5 to its full limit in one direction, is constructed in the following manner:

65 Threaded on the member 29 within the

pawl trip member 21 is a pawl trip operating member 39 formed at diametrically opposite sides with tongues or fingers 40, one of which is receivable in each of said grooves 22, and said member 39 on opposite faces 70 at diametrically opposite sides is provided with a projection 41 which are adapted to interlock with corresponding projections 42 extending outwardly from opposing faces of limiting nuts 43 having threading engagement with the member 29 in spaces relative to each other.

The position of the nuts 43 limits the travel of the member 39 longitudinally of the shaft 29 on the rotation of the shaft, 80 due to the gear connection with the nut 9.

Lock nuts 44 retain the nuts 43 in their adjusted position, and on the travel of the member 39 its full distance in either direction, one of the lugs 41 thereof engaging a 85 lug 42 on one of the nuts 43, prevents further travel of the member 39, which operation causes the member 39 to make a slight rotation with the shaft 29, partially rotating the member 21, which in turn causes the 90 operation of the pawls 36 and 37 to release one from contact with the ratchets 35 and throw the other in engagement therewith.

The device being constructed and assembled as in the drawings and positioned as in 95 Figs. 1 and 3, the same operates in the following manner:

Motion being imparted to the arm 6 to oscillate the pipe 5, the pawl 36 causes a rotative movement of the nut 9 with the 100 pipe owing to the tight frictional contact between the nut 9 and the sleeve 8, but the pawl 36 which is in engagement with the ratchets 35 interrupts the rotative movement of the nut 9 in one direction and on the upward movement of the arm 6 the action of this pawl in arresting the rotation of the nut 9 causes the nut to impart a slight longitudinal movement to the pipe 5. On the successive rotative movement of the nut 9 110 the gear 32 carried thereby imparts rotation through the pinion 31 to the shaft 29 and this rotative movement of the shaft causes a longitudinal movement of the pawl trip operating member on the shaft 29 as 115 the counter-weight 25 holds the trip member 21 in the position as in Fig. 4 of the drawings. The successive intermittent partial rotation of the shaft 29 causes a movement of the member 39 to its full limit in one 120 direction, at which time the lug 41 thereof engages the lug 42 on the retaining nut, and this engagement locks the member 39 and the retaining nut 43 which limits the movement of the member in one direction 125 and on the successive partial rotation of the shaft 29, the members 40 received in the slot 22 cause a partial revolution of the pawl trip member 21, which, in its movement, disengages the pawl 36 from the ratchets 130

35 and permits the engagement of the pawl 37 therewith.

This operation on successive reciprocations of the arm 6 will cause a rotation of 5 the nut 9 in the opposite direction, which will also impart rotative movement to the shaft 29 to cause the member 39 to travel toward the limiting nut 43 adjacent the opposite end of said shaft 29, at which time a 10 partial revolution will be imparted to the member 21 returning it to its former position to disengage the pawl 37 from the ratchets 35 and position the pawl 36 to engage therewith.

15 It will be apparent that the distance between the limiting nuts 43 controls the reciprocating movement of the pipe 5, and any variation in this distance will correspondingly vary the travel of the pipe 5.

20 Having thus described our invention, what we claim as new and desire to protect by Letters Patent is:—

1. In combination with a pipe capable of longitudinal and alternating rotary movement, a member having threaded connection with the pipe and capable of rotation about the same to impart a longitudinal reciprocating movement thereto in either direction, means for holding said member from longitudinal movement with the pipe, devices co-operating with said member for retaining the same in its rotated position, means for operating said member and for imparting a rotary movement to said pipe, mechanism 25 co-operating with said devices for actuating the same to automatically reverse the direction of rotation of said member to reverse the direction of longitudinal movement of said pipe on the movement of the same to 30 the end of its stroke in one direction.

2. In combination with a pipe capable of reciprocating and rotary movement, means for imparting an alternating rotary movement to said pipe, means for imparting a reciprocating movement to the pipe during 45 the rotation thereof, and devices for automatically reversing the direction of longitudinal movement of the pipe on the same arriving at the end of its longitudinal 50 movement in either direction.

3. In combination with a pipe capable of reciprocating and alternating rotary movement, means for imparting an alternating rotary movement to said pipe, means rotatable with said pipe for imparting a longitudinal movement to the same during the rotation thereof, and means for controlling the movement of said rotatable means for automatically reversing the direction of longitudinal 55 movement of the pipe on the same arriving at the end of its stroke in one direction.

4. In combination with a pipe capable of reciprocating and alternating rotary movement, means for imparting an axial oscillat-

ing movement to said pipe, a nut mounted on said pipe for rotation with the same during its rotary movement and held from longitudinal movement with said pipe, devices capable of positioning to co-operate 70 with said nut to prevent its rotation in one direction with the rotation of said pipe, whereby said nut imparts a longitudinal movement to the pipe, and mechanism for operating said devices to automatically reverse 75 the direction of longitudinal movement of said pipe on the completion of its movement in one direction.

5. In combination with a pipe capable of reciprocating and alternating rotary movement, means for imparting an alternating rotary movement to said pipe, a nut threaded on said pipe for rotation about the same and movable with said pipe during the alternate rotation thereof, devices capable of 80 positioning to co-operate with said nut to prevent its rotation in one direction with the rotation of said pipe in that direction, and mechanisms operated by the rotation of said nut for operating said devices to cause 85 the same to automatically reverse the direction of reciprocation of said pipe on the completion of its movement in one direction.

6. In combination with a pipe capable of alternating rotary and longitudinal reciprocating movement, means for imparting alternating rotary movement to the pipe, a nut having threaded engagement and tight frictional contact with the pipe and adapted for rotation therewith on the rotation of the 95 pipe, a pair of pawls arranged in co-operating relation with the nut and adapted for selective engagement with the nut to prevent the rotation thereof in one direction, thereby controlling the direction of movement 100 of the pipe, and mechanism for operating said pawls whereby the direction of rotation of said nut is reversed and the direction of longitudinal movement of the pipe is reversed on the same reaching the 110 end of its stroke in one direction.

7. In combination with a pipe capable of alternating rotation and longitudinal reciprocating movement, means for imparting rotative movement to the pipe, a nut having 115 threaded engagement and tight frictional contact with the pipe and adapted for rotation therewith on the rotation of the pipe, means for holding the nut from movement longitudinally with the pipe, a pair of pawls 120 carried by a stationary member and adapted for co-operation with the nut for controlling the direction of rotation thereof, means for tripping said pawls to remove one from engagement with the nut and permit the engagement of the other with the nut, and means co-operating with said nut and with said pawl tripping means for operating said means to trip said pawls whereby the direction of reciprocation of said pipe is reversed 125 130

on the same arriving at the end of its stroke in one direction.

8. In combination with a pipe capable of longitudinal movement, means for imparting alternating rotary movement to said pipe, means for imparting longitudinal movement to the pipe during the rotative movement thereof, and devices for automatically reversing the direction of longitudinal movement of the pipe on the same arriving at the end of its longitudinal movement in either direction.

9. In combination with a pipe capable of longitudinal movement and of rotary move-

ment during said longitudinal movement, of means for imparting rotary movement to the pipe and longitudinal movement, and means for alternating the direction of longitudinal movement of said pipe.

In testimony whereof we have signed our names to this specification in the presence of two subscribing witnesses.
